HAT BLOCKING AND STORING DEVICE

Thomas A. Brennan, Washington, D. C.

Application August 5, 1932, Serial No. 627,664

5 Claims. (Cl. 223—24)

This invention relates to hat blocking and storing devices and to a new and improved method of making the same.

Heretofore hat blocking devices had been made in two forms, namely, wood or metal castings.

It has been found that wood is unsatisfactory for the reason that whenever a wooden form is dropped or struck with any hard object it becomes dented and thus loses its most important function which is to serve as a smooth support so that hats can receive the same smooth contour as that of the wooden insert or form.

Castings are objectionable, first, because of the undue amount of metal which must be used, thus rendering such devices almost prohibitive due to the expense involved.

It may be said wooden forms are also expensive.

20 Castings are additionally objectionable because of the weight of forms made in this manner. Such weight tiring the hat blocker and obviously affecting the efficiency of his work.

It is accordingly an object of the invention 25 to provide a means for supporting a hat during blocking and pressing operations. In the preferred form this means comprises a combination of an insert or form having the same shape generally as a hat and a rim supporting member which is adapted to receive a rim of a hat during pressing and blocking operations.

It is a further object of the invention to provide a means which has another function, that is to serve as a supporting medium for hats being shipped.

It is the present practice to ship hats in rather fragile containers which if subjected to rough treatment necessitates re-blocking of the hats at their point of destination. The invention hereafter to be described overcomes this difficulty by providing an exceedingly cheap supporting means for hats in transit.

The annexed drawing and the following description set forth in detail certain structure 45 embodying the invention, such disclosed means constituting, however but one of various mechanical forms in which the principle of the invention may be used.

In said annexed drawing Fig. 1 is a vertical 50 central section of a hat supported by a crown insert.

Fig. 2 is a central vertical section of a hat supported by a rim member.

Fig. 3 is a detail of a modification of a supporting post shown in Fig. 1.

Fig. 4 is a modification of the supporting post shown in Fig. 2 and

Fig. 5 is a still further modification of a supporting post.

Referring now to the drawing in Fig. 1, a 5 hat H is illustrated having a crown portion 1 and a rim portion 2. The inner surface 3 of said crown being seated upon the outer surface 4 of a member which I shall term an insert. In the prior art such members have received 10 various names such as blocks, forms, etc. The rim 2 has an upper surface 5 and a lower surface 6 which are operated upon in a subsequent operation to that upon the crown portion 1. The insert 4 is hollow and may be 15 formed of either flat sheet metal or tubular stock. Where sheet metal is used the insert 4 is stamped between appropriate dies to impart thereto the general configuration of a hat. It will be noted that the lower edge 7 of 20 this insert is supported on posts 8, 9 and 10 (there being a fourth post not shown). It will also be observed that the edge 7 extends below the under surface 6 of the rim portion so that the insert supports the hat away from the table or work bench in the event that the supporting posts are not used. These supporting posts have grooves so as to engage the lower edge 7 of the insert and to hold it in elevated 25 position where the hat operator may most easily perform his work.

In the event that the insert is made from tubular material, a section of a tube has one end received in an appropriate die after which a second die approaches the tubular section and closes the end approached to form a smooth surface having the general shape of a hat crown.

Referring now to Fig. 2 a ring member 14 is 40 illustrated which has an upper surface 15 upon which the surface 6 of the rim 2 is adapted to be seated. The ring member has an outer portion 16 which extends substantially in a vertical direction and a lower edge 17 which is received in grooves in supporting posts 18, 19 and 20. 45 These posts have a length which is sufficient to support a crown 1 out of engagement with the table or work bench. The vertical portion 16 extends upwardly and is then rounded to merge into the portion 15. The distance between edge 17 and the uppermost part of the upper surface 15 being illustrated in Fig. 2 as A. This distance is exactly equal to the distance between the edge 7 and the lower surface 6 of the rim 2 in Fig. 1, said last named distance being designated 50 55

as B, in Fig. 1. The purpose of forming the insert 4 and the ring member 14 with such distances equal is to provide a means for supporting hats during shipment. By simply removing 5 the posts 8, 9 and 10, etc., an insert is available for maintaining a stack of hats in a predetermined shape regardless of the manner in which they are shipped and the treatment to which they are subjected during transit. In practice 10 a hat is slipped over the insert 4 and the ring member 14 is then slipped over the hat, thus providing means for rigidly supporting the crown and rim of a hat or series of hats. A second ring member is preferably used beneath 15 the lowermost rim and if desired more rings may be used.

In Fig. 3 a modified means of supporting an insert is illustrated. In this modification the insert 4' has a projection which may take the 20 form of a lug 25 and this lug has an aperture thereon which is screw threaded to receive the post 8'.

In Fig. 4 the same means is disclosed for use with the ring member 14'. In this instance, a 25 lug 26 has a screw threaded aperture adapted to receive the supporting post 20'.

The post 30 illustrated in Fig. 5 is screw threaded as shown in 31 and also has a slot 32 so that it may be used with either embodiment 30 of the invention.

It is believed that the object and advantage of applicant's improved device are fully apparent, however it may be well to note that applicant's storing and blocking device is exceedingly 35 cheap to manufacture yet possesses more strength than devices used for the same purpose of the prior art and in addition is capable of two extremely valuable uses. The use of a hat blocking insert as a means for supporting 40 hats during shipment has hertofores been utterly impractical due to the weight of such devices. In sharp distinction to this the applicant has provided a strong, light device which is fully capable of supporting hats during transit so 45 that they may be received in the same condition as when they left the factory.

Other modes of applying the principle of my 50 invention may be employed instead of the one explained, change being made as regards the mechanism herein disclosed, provided the means stated by any of the following claims or the equivalent of such stated means be employed.

I therefore particularly point out and distinctly claim as my invention:

55 1. A hat cleaning and pressing device comprising a ring member of sheet metal, having the

general contour of a rim of a hat, said member being adapted to support the rim of a hat in inverted position, the outer periphery of said member terminating in a substantially vertical flange, said member having an upper substantially horizontal surface with a curved surface 5 connecting said horizontal surface and said vertical flange.

2. A hat blocking device comprising a ring member of sheet metal, having the general contour of a rim of a hat, said member being adapted to support the rim of a hat in inverted position, the outer periphery of said member terminating in a substantially vertical flange and posts engaging said flange and supporting 10 15 said member in elevated position.

3. A device of the character described comprising a hollow metal insert having the general configuration of the crown of a hat with a smooth continuous surface, said insert having 20 an open end for the reception of the hand of a presser and being formed of sheet metal, said insert being adapted to be placed within a crown of a hat for use in pressing, said insert being adapted for use in pressing a multiplicity 25 of hats of different sizes.

4. A device of the character described comprising a hollow metal insert having the general configuration of the crown of a hat with a smooth continuous surface, said insert having 30 an open end for the reception of the hand of a presser and being formed of sheet metal, said insert being adapted to be placed within a crown of a hat for use in pressing, said insert being adapted for use in pressing a multiplicity 35 of hats of different sizes, the side walls of said insert having a length so as to normally extend below the brim of a hat being pressed.

5. A home hat pressing set comprising a hollow metal insert having the general configuration of the crown of a hat with a smooth continuous surface, said insert having an open end for the reception of the hand of a presser and being formed of sheet metal, said insert being adapted to be placed within a crown of a hat 40 45 for use in pressing, said insert being adapted for use in pressing a multiplicity of hats of different sizes, a ring member of sheet metal, having the general contour of a rim of a hat, said member being adapted to support the rim of a hat in inverted position, the outer periphery of said member terminating in a substantially vertical flange and posts engaging said flange and supporting 50 55 said member in elevated position.

55 THOMAS A. BRENNAN.
